UNITED STATES PATENT OFFICE.

ROLAND L. YARBERRY, OF SAN ANTONIO, TEXAS.

DOOR-BOLT.

1,300,912.

Specification of Letters Patent. Patented Apr. 15, 1919.

Application filed July 20, 1918. Serial No. 245,917.

To all whom it may concern:

Be it known that I, ROLAND L. YARBERRY, a citizen of the United States, residing at San Antonio, in the county of Bexar and 5 State of Texas, have invented new and useful Improvements in Door-Bolts, of which the following is a specification.

This invention relates to new and useful improvements in devices for holding doors 10 in open position while the locks are being applied thereto.

The invention, among other features, comprises a casing with means for clamping it to the bottom edge of a door, a bolt carried 15 by said casing and a frictional block on the end of the bolt for engaging the floor for holding the door against movement.

Another object of the invention is to provide a device of this character which is simple and durable in construction, reliable and efficient in operation and one which can be manufactured and placed upon the market 20 at a minimum cost.

The invention also consists in certain other 25 features of construction and in the combination and arrangement of the several parts, to be hereinafter fully described, illustrated in the accompanying drawings and specifically pointed out in the appended claim.

30 In describing my invention in detail, reference will be had to the accompanying drawings wherein like characters denote like or corresponding parts throughout the several views, and in which:—

35 Figure 1 shows my invention applied to a door with the parts in operative position.

Fig. 2 is an edge view with the bolt in retracted position.

40 Fig. 3 is a view of the casing with the top removed.

Fig. 4 is a longitudinal section.

Fig. 5 is a sectional view of the bolt.

Fig. 6 is a cross section on line 6—6 of Fig. 2.

45 As shown in these views the device consists of a casing 1 provided with a removable cover or face plate 2 and carrying a bolt 3. The casing comprises the sides 4 and 5 extending at right angles to each other, and

the end 6. The side 5 is provided with a 50 central screw threaded hole 7 and with plain holes 8 adjacent each end thereof. This casing is adapted to be placed over the bottom edge of the door with the lower corner of the door engaging the closed end of the 55 casing. The face plate 2 is then placed in position and is held to the side 5 by means of the pins 9 entering the holes 8 and the thumb bolt 10 engaging the screw threaded hole 7. When the screw bolt is screwed up 60 the parts will be clamped to the door. In this manner the device may be placed on doors of different thicknesses. The side 5 carries the bolt 3, said bolt consisting of the base 11 having the circular part 12 in which 65 the bolt proper 13 fits. A coil spring 14 in the end of the circular part 12 tends to force the bolt downwardly with its end projecting from the casing. The bolt is provided with a hand engaging part 15 which passes 70 through an elongated slot 16 formed in the circular casing and provided with a lateral extension 17 to receive said part 15 to hold the bolt in retracted position. The end of the bolt is provided with a rubber head 18 75 which is adapted to engage with the floor when the bolt is forced downwardly by the spring and thus hold the door against movement.

By the use of my device the knobs and 80 locks may be applied to the door without having to hold said door in open position by the knees or feet of the workman as is now necessary.

While the invention is more particularly 85 adapted for carpenters in fitting locks to doors it will, of course, be understood that the device may be used for other purposes.

It is thought from the foregoing description that the advantages and novel features 90 of my invention will be readily apparent.

I desire it to be understood that I may make changes in the construction and in the combination and arrangement of the several parts, provided that such changes fall within 95 the scope of the appended claims.

What I claim is:—

A device for clamping a bolt to a door

comprising a casing consisting of two sides extending at right angles to each other and an end plate for engaging one side, the edge and bottom of the door, one side having a central screw threaded hole in its edge and a pair of plain holes, a cover plate for engaging the other side of the door, guide pins on

said plate engaging with the plain holes, a thumb bolt on said plate engaging the screw threaded holes for adjustably clamping the 10 plate to the side and a spring operated bolt carried by said casing.

In testimony whereof I affix my signature.
ROLAND L. YARBERRY.

Copies of this patent may be obtained for five cents each, by addressing the "Commissioner of Patents, Washington, D. C."
